(57) **CLAIM**

The ornamental design for a blended door latch assembly, as shown and described.

DESCRIPTION

FIG. 1 is a perspective view of a blended door latch assembly;

FIG. 2 is a top plan view of the blended door latch assembly of FIG. 1;

FIG. 3 is a front elevation view of the blended door latch assembly of FIG. 1;

FIG. 4 is a right side elevation view of the blended door latch assembly of FIG. 1;

FIG. 5 is a rear elevation view of the blended door latch assembly of FIG. 1;

FIG. 6 is a left side elevation view of the blended door latch assembly of FIG. 1; and,

FIG. 7 is a bottom plan view of the blended door latch assembly of FIG. 1.

Portions of FIGS. 1 through 7 are shown in broken lines illustrating portions of the article of manufacture that form no part of the claimed design.

1 Claim, 7 Drawing Sheets
